UNITED STATES PATENT OFFICE.

WILLIAM RENNY WATSON, OF GLASGOW, SCOTLAND.

MACHINE FOR CUTTING OR SLICING SUGAR-CANE, &c.

SPECIFICATION forming part of Letters Patent No. 494,946, dated April 4, 1893.

Application filed July 7, 1892. Serial No. 439,272. (No model.)

To all whom it may concern:

Be it known that I, WILLIAM RENNY WATSON, engineer, of the Mirrlees Watson & Yar-

yan Company, Limited, of 45 Scotland Street,
5 Glasgow, in the counties of Lanark and Ren-
frew, Scotland, have invented Improvements
in Machinery for Cutting or Slicing Sugar-

Cane or Analogous Saccharine Plants, of which

the following is a specification.

10 My invention relates to improvements in
machinery for cutting or slicing sugar canes
or analogous saccharine plants preparatory to
the process of extraction of the juice by dif-
fusion, and has for its object the saving of la-
15 bor and improved cutting or slicing of the
canes.

My invention consists of two disks or cones
revolving toward one another and so close to-
gether that they almost touch. These disks
20 or cones are fitted with the usual cutting or
slicing knives, and the canes are fed to these
cutting or slicing knives by means of roll-
ers driven at a suitable speed from the shaft-
ing that drives the cutting disks or other suit-
25 able moving shaft or motor.

In the drawings, Figure 1 is a plan of the
machine with two revolving disks. Fig. 2 is
an elevation of Fig. 1. Fig. 3 is an end view
30 of Fig. 1 showing the disks. Fig. 4 is a plan
of the machine with two revolving cones. Fig.
5 is an elevation of Fig. 4. Fig. 6 is an end
view showing face of one cone and side of the
other. Fig. 7 is an enlarged plan view of the
35 cones A and A'. Fig. 8 is a front view of the
cutter-box and blade, and Fig. 9 is a section
on line x—x Fig. 8. Fig. 10 shows the endless
conveyer in side elevation with its driving
wheel.

A, A', are the revolving disks or cones fit-
40 ted with the cutting or slicing knives B, B,
driven by suitable mechanism in the direc-
tion shown by the arrows, always toward each
other, from their upper peripheries.

In Fig. 1 the axes of the cutting disks are
45 parallel and the radial knives or cutters
which extend to the peripheries are placed on
the front faces, in suitable boxes as shown in
detail in Figs. 7, 8 and 9. The box b is se-
cured in the disk by any suitable locking de-
50 vice, the blade being fastened by the screws

c, c. As shown in Figs. 3 and 8 the blades
may be grooved, so that a crushing or tearing
of the cane takes place if found more desir-
able.

In Fig. 2 the feeding mechanism of well-
known form, is shown with the endless band-
carrier G, driven in unison with the two sets
of feed rollers E and F. These rollers may be
fluted or plain, and only one set may be used.
These rollers guide the cane down the in-
clined chute S, to the ledger plate L which is
shown stationary, but may be provided with
adjusting means. Also in Fig. 2 the disk A
is shown removed and the cutter or disk A' is
65 shown in section, showing the blade in a par-
allel position and midway between the top
plate P, (shown more clearly in Fig. 3) and
the ledger plate L.

Figs. 4, 5 and 6, show a modification hav-
ing cones to hold the blades, which brings the
70 axes of the disks at right angles to each other,
so that bevel gear may be used, driving both
from one shaft. As shown, the radial knives
or cutters of the two revolving cutter-bearing
disks A and A' meet and extend across the
75 line of feed, and the cane as it is fed down
between the plate P and ledger plate L, first
receives a shearing action from the side of
the chute toward the center, then as the
80 blades pass a line drawn from their centers
the cut is vertical ending in a shearing action
from the center of the chute, outward. This
prevents the crowding of the cane to one side
85 as would occur where only one disk with cut-
ters the whole width of the chute was used,
the knives necessarily being twice the length
of those shown. My invention not only com-
bines the advantage as above cited but the
knives being shorter, are easier handled, for
grinding.

Having thus described my invention, what
I claim is—

1. In combination, with the feeding mech-
anism, and the two revolving disks or cones
which have their cutters pass the ledger plate
95 in the same vertical plane, substantially as
described.

2. In combination, the feeding mechanism,
the two adjacent revolving disks or cones in
the same plane having suitable knives or cut-
100

ters substantially as and for the purpose set forth.

3. The combination of a suitable feed, and two revolving cutter-bearing disks, whose cutters are radially arranged and whose cutting faces together, extend across the line of feed whereby they shear in opposite directions and toward the center, as and for the purpose set forth.

In testimony whereof I have signed my name to this specification in the presence of two witnesses.

WM. RENNY WATSON.
